UNITED STATES PATENT OFFICE.

IRVING C. JENNINGS, OF SOUTH NORWALK, CONNECTICUT.

PUMPING APPARATUS FOR HANDLING GASES AND LIQUIDS.

Application filed September 6, 1927. Serial No. 217,669.

The object of this invention is to provide a very simple pumping apparatus for handling both gases and liquids. The apparatus has been especially designed for use in vacuum steam heating systems, for use in paper mill work, and for use in pump work such as removing drainage or sewage.

The invention comprises a simple modification of the well-known Nash air or gas pump, which is covered by patents granted to Lewis H. Nash, No. 953,222, dated March 29, 1910 and No. 1,091,529, dated March 31, 1914, and which in improved form is shown in patent granted to me No. 1,297,692, dated March 18, 1919.

The invention is illustrated in the accompanying three sheets of drawings in which—

Figure 1 is a diagram illustrating the piping connections,

Figure 2 is a plan of the pump and the motor employed for driving the same,

Figure 3 is a cross-sectional elevation on an enlarged scale on the line 3—3 of Figure 2, illustrating the ports and connections employed for pumping the liquid,

Figure 4 is a cross-sectional view on the line 4—4 of Figure 2, illustrating the gas inlet and outlet ports of the pump, and

Figure 5 is a view similar to Figure 1, illustrating a modified form of piping.

The Nash pump before referred to comprises a rotor having displacement chambers on its periphery arranged in a casing shaped eccentrically relatively to the rotor.

This casing is provided with ports. The pump is partly filled with a liquid, as water. As the rotor is driven at high speed, this liquid will assume a ring shape around inside of the casing and will recede from the chambers by centrifugal action and will be forced into the chambers by its velocity and the crowding-in action against the casing, so that in effect the liquid will form water pistons reciprocating into and out of the displacement chambers. A pump of this character is particularly adapted to handle a gas, and although it will handle a liquid, it does not do so efficiently. The object of this invention is to re-arrange this pump so that

it will handle both gases and liquids efficiently.

To do this, I provide an outlet or port or outlets or ports in the casing at the point or points where the liquid is being crowded inwardly into the displacement chambers, and connect the same preferably to an hy-

drostatic head, so that when any excess liquid passes to the pump, it will be pumped out against this hydrostatic head. By this arrangement, the pump can be used to maintain a vacuum by exhausting air and gas, and also to pump efficiently any liquid drawn along with the air or gas; or, in other words, one rotor can be adapted for efficient use in any location where both gases and liquids have to be handled.

Referring to the drawings and in detail, A designates the pump casing, in which is arranged the rotor B provided with the usual displacement chambers. The casing is arranged with two eccentric sections, so that two pumping actions will be obtained in each displacement chamber for each rotation of the rotor. Suitable gas inlet ports C, C and gas outlet ports D, D are provided in the side of the casing to cooperate with the side of the rotor B, as shown in Figures 3 and 4. The construction thus far described is a well known form of Nash pump. When this pump is filled with a liquid, the same will act to pump gas.

If my improved pump is to be used in a vacuum steam heating, the returns, which are to be handled, are lead to the pump through an inlet pipe E, which connects to the inlet ports C, C; and the air or gas, which is to be exhausted, is forced out through an outlet pipe F which is connected to the outlet ports D, D.

Outlets or ports G, G are formed in the pump casing at the points where the operating liquid tends to exert its maximum compression effect, or where it is forced most completely into the displacement chambers. Pipes H, H are connected to these outlets or ports, and these pipes preferably connect to a single pipe I, which is carried upwardly for a considerable height and then connected to a header J. The pipe I is carried up high enough so as to give any desired hydrostatic head back into the pump casing. The water or liquid handled by the pump and delivered over into the header J can be taken therefrom through a pipe K. If the apparatus is used in vacuum steam heating, this pipe K can be connected to the boiler through a suitable check valve, the hydrostatic head serving to force the water into the boiler against the pressure therein.

In operation, when air or gas only is being handled, the pump will act as an ordinary Nash pump and will exhaust the air

or gas by the piston action of the water in the displacement chambers of the rotor and force the same out through exhaust ports D D and outlet pipe F.

- 5 When liquid or water comes in through the inlet pipe E, the pump will contain an excess of operating water. This will tend to create an excess pressure at the points G G in the pump casing; and this, instead of 10 effecting a heavier pumping action on the air or gas, will cause the water to raise or back up in the pipe I and flow over into the header J. This surplus water thus will be easily and smoothly handled as it does not 15 have to be forced into the displacement chambers of the rotor and out through the outlet ports D D, which occasions banging or water hammer. When the rotor is handling water, it will be seen that the same 20 acts substantially like a centrifugal water pump, the inlet ports C C representing the inlets or eye, connecting to the impeller, and the water being thrown outwardly in the impeller and clearing therefrom beyond the 25 periphery thereof into the outlets G G.

The pump will act to maintain a substantially constant vacuum or suction, as the pressure of the water pistons entering into the displacement chambers of the rotor is 30 substantially determined by hydrostatic head in the pipe I.

Thus, both gas and liquid can be handled efficiently by one rotor and if desired, the apparatus can be designed to work without 35 the separating tank usually employed in systems of the character referred to.

In the same manner the pump can be used in paper mill work.

In some instances only one water outlet 40 or port can be used in the pump casing. This arrangement is illustrated in Figure 5 of the drawings. This arrangement can be used where the volume of liquid is small relatively to the volume of air or gas which 45 is to be handled or where the pump casing has only one eccentric section.

The apparatus can be used as a sump pump, in which the pumping apparatus is placed above the sump. When put in this 50 location and started in operation, the pump will first act to exhaust air from the pipe leading up from the sump. This will lift the water up to the pump which will thereafter act as a centrifugal pump, lifting and 55 pumping the water from the sump. In effect, then the pump will act as a self-starting, lifting, and forcing centrifugal water pump.

The details and arrangements herein shown 60 and described may be greatly varied by a skilled mechanic without departing from the scope of my invention as expressed in the claims.

Having thus fully described my inven-

tion, what I claim and desire to secure by 65 Letters Patent is:—

1. In a pump, employing liquid as the pumping medium, a rotor having displacement chambers, a casing arranged eccentrically to the rotor, a gas inlet and outlet, and 70 a liquid outlet or port arranged at a point in the casing where the operating liquid tends to exert a compression effect.

2. In a pump, employing liquid as the pumping medium, a rotor having displacement chambers, a casing arranged eccentrically to the rotor, a gas inlet and outlet, and a liquid outlet or port arranged at a point in the casing where the operating liquid 75 tends to exert its maximum compression effect. 80

3. In a pump employing a liquid as the pumping medium, a rotor having displacement chambers, a casing having a plurality of section arranged eccentrically to the rotor, gas inlet and outlet ports, and liquid outlets or ports arranged at points in the casing where the operating liquid tends to exert a compression effect. 85

4. In a pump employing a liquid as the pumping medium, a rotor having displacement chambers, a casing arranged eccentrically to the rotor, a gas inlet and outlet, a liquid outlet or port arranged at a point in the casing where the operating liquid tends to exert a compression effect, and an outlet 90 pipe connected to the liquid outlet or port and carried up for a considerable height so as to give a hydrostatic head back into the pump casing, whereby the pump is arranged to handle both gases and liquids. 100

5. In a pump employing a liquid, as the pumping medium, a rotor having displacement chambers, a casing having two sections arranged eccentrically to the rotor, gas inlet and outlet ports, liquid or outlet ports arranged at points in the casing where the operating liquid tends to exert a compression effect, and a pipe connected to the liquid outlet or ports and carried up to a considerable height so as to provide a hydrostatic 105 head back into the pump casing whereby the pump is arranged to handle both gases and liquids. 110

6. In a pump employing a liquid as a pumping medium, a rotor having displacement chambers, a casing arranged eccentrically to the rotor, a gas inlet and outlet, a liquid outlet or port arranged at a point in the casing where the operating liquid tends to exert a compression effect, an outlet 115 pipe connected to the liquid outlet or port and carried up to a considerable height so as to provide a hydrostatic head back into the casing, and a header into which the outlet pipe connects. 120

In testimony whereof I have hereunto affixed my signature.

IRVING C. JENNINGS.
